FIG. 1

FIG. 3

FIG. 2

FIG. 4

Figure 1 is a front elevational view of my design for a portable radio cabinet as it appears with its handle in an upwardly extended carrying position;

Figure 2 is a side elevational view of my design with its handle in a downwardly and rearwardly extended position to serve as a support for the radio cabinet when it is placed on a horizontal surface;

Figure 4 is a fragmentary cross-sectional view taken on the line 4—4 of Figure 1 which further illustrates the contours and configurations of the speaker grille and front panel of my design; and

Figure 5 is a perspective view of my design at it appears with its handle in a retracted position to facilitate insertion of the radio in a pocket or carrying case.

The bottom and back of the portable radio cabinet are substantially plain and unornamented.

The dominant features of my design reside in the portion shown in full lines.

I claim:

The ornamental design for a portable radio cabinet, substantially as shown and described.
